EXTENSION TABLE

Jacob S. Knechtel, Hanover, Ontario, Canada

Application January 14, 1932. Serial No. 586,636

4 Claims. (Cl. 45—112)

The principal objects of this invention are to provide an extension table which may be operated with very great ease to either extended or closed positions, and to devise a construction of 5 extremely simple form which will be inexpensive to manufacture and very dependable in operation.

A further object is to provide an extension table with an extension leaf having side rails 10 corresponding with the side rails of the table top.

The principal features of the invention consist in the novel arrangement of an extension leaf between the extension slide and the permanent table top whereby said leaf is retained in its central position and in the novel construction and arrangement of a lever carried by the adjustable slide and co-operating with cam blocks on the extension leaf whereby said leaf is raised or lowered vertically.

20 A further feature of importance consists in the arrangement of hinged side rails corresponding with the side rails of the table mounted on the extension leaf to complete the side rail of the table when in its extended position.

25 In the accompanying drawings, Figure 1 is an underside plan view of my improved table top shown in the closed position.

Figure 2 is an underside plan view of the table top shown in the extended position, one of the 30 side rails on the extension leaf being folded and the other opened to the extended position.

Figure 3 is a cross sectional view through the line 3—3 of Figure 1.

Figure 4 is a longitudinal sectional view of one 35 end of the table, taken through the line 4—4 of Figure 1.

On reference to the accompanying drawings it will be seen that the table top is formed of two movable portions 1 and 2 which are preferably constructed with the moulded side rails 3. The outside extension slide bars 4, which are of the usual construction, are here shown secured to the underside of the top of the movable portion 1 and the inside slide bars 5 are secured to 40 the underside of the top of the movable portion 2 and between these are arranged the central slide bars 6, each set of bars being slidably connected in the usual manner by dove tail tongue and groove slide connection.

50 The centre bars 6 are of slightly greater depth than the bars 4 and 5 and the top and bottom surfaces thereof extend slightly above and below the inside and outside bars.

The centre bars are supported on any desirable form of leg supports 7.

In the centre of each of the bars 6 and on the underside is pivotally mounted a spur gear 8 and rack bars 9 secured to the underside of the inner and outer slide bars mesh with these gears to operate both ends of the table simultaneously. 60

This arrangement of spur gears and racks is quite common.

The outside and inside slide bars are spaced from the underside of the table top by the bars 10 and 11 respectively, the space being slightly 65 greater than the thickness of the table top. These spacer bars extend from the outside ends of the table top inwardly and the inner ends are spaced apart a distance slightly greater than the width of the extension leaf 12, which rests 70 between them upon the top of the centre extension bar.

Each of the centre extension bars is provided with a vertical hole 13 which is slightly offset from the pivot of the gears and pins 14 secured 75 in the leaf 12, preferably centrally thereof, extend into these holes and fit quite loosely therein. These pins hold the extension leaf in a centralized position both longitudinally and transversely of the table. 80

Bars 15 are secured to the underside of the extension leaf preferably outside of the extension slide bars and are adapted to engage the underside of the portions 1 and 2 to ensure the alignment of the leaf with the table top when 85 the leaf is raised and also to prevent the displacement of the leaf.

A pair of cam blocks 16 and 17 are secured in offset relation to the underside of the leaf 12 preferably adjacent to the longitudinal edges. 90 These blocks are formed with bevelled inward ends.

A cross bar 18 is secured between the inside slide bars 5 and is preferably set diagonally, the ends thereof being rabbeted into grooves 19 in 95 the inner sides of said bars.

A lever 20, which may be formed of a bar of wood, is pivotally mounted on a bolt 21 secured in the cross bar 18. This lever is preferably of angled form, the inward end 22 thereof being cut 100 to extend at an obtuse angle from the outer portion. This lever is adapted upon being swung on its pivot to engage the bevelled end of both of the cam blocks 16 and 17 simultaneously when the table portions 1 and 2 have been drawn out to 105 their extended position and the swinging movement causes the cam blocks to rise on the lever, thereby lifting the table leaf into a position level with the end portions 1 and 2.

A cross bar 23 is preferably arranged between 110

the ends of the inner extension bars 5 to support the outward end of the lever which extends close to one end of the table, and a knob 24 is arranged on the lever end to be grasped by the hand of the operator for the purpose of swinging the lever.

Moulded rail portions 25 corresponding with the moulded rail 3 are secured to the underside of the leaf 12 by friction hinges which will hold the rails in either the folded-in position as shown in Figure 1 or in the extended position in alignment with the side rails of the table. Such friction hinges are quite commonly known in the furniture art and their construction need not be described in detail.

It will be readily appreciated that a table constructed as described is of very simple form and its operation is so simple that even a small child can quite easily operate it.

To operate the table it is merely necessary to pull upon either end when the movable portions 1 and 2 will slide apart to their maximum position. This movement brings the pivot bolt of the lever 20 to a central position as shown in Figure 2 underneath the extension leaf. By reaching under the table top and grasping the knob 24, the operator then merely swings the lever on its pivot and the lever engaging the bevelled ends of the cam blocks lifts the leaf into a position level with the table top, it being held to its central position by the pins 14 engaging the sides of the holes 13.

The leaf will be held in its raised position supported by the rigid lever with the extending ends of the cross bars 15 preferably snugly engaging the underside of the adjacent table top sections 1 and 2. The side rails are then swung downwardly and the ends of the table can then be moved inwardly to close tightly against the centre leaf.

In closing the table it is merely necessary to fold in the side rails, swing the lever 20 on its pivot to lower the centre leaf, then push the end members together.

What I claim as my invention is:

1. In an extension table, the combination with a pair of table tops mounted upon extension slides, of a leaf housed beneath the movable

members of the table top and supported on said extension slides, means for holding said leaf from lateral or longitudinal displacement, a cross bar extending between and connected with the inner extension slides, a pivot bolt secured to said cross bar, a lever pivoted on said pivot bolt above the cross bar and extending transversely of said leaf, and bevelled blocks arranged on the underside of said leaf and directly engaged by said lever at spaced points either side of its pivot.

2. In an extension table, the combination with a pair of separable table tops mounted on extension slides, of a leaf member housed beneath the table tops and movable vertically, cam blocks sloping longitudinally of the leaf at the side edges thereof, and a lever pivotally supported on a vertical pivot below said leaf and extending longitudinally between said extension slides and directly engaging said cam blocks in its swinging movement to raise and lower said leaf.

3. In an extension table, the combination with a pair of separable table tops mounted on extension slides, of a leaf member housed beneath the table tops and movable vertically, cam blocks sloping longitudinally of the leaf at the side edges thereof, a lever pivotally supported on a vertical pivot below said leaf and extending longitudinally between said extension slides and directly engaging said cam blocks in its swinging movement to raise and lower said leaf, said lever being of angled form with the inner and outer portions thereof radiating from said pivot in angular relation to each other, and a handle extension from the outer portion of said lever accessible between the slide extensions at the end of the table.

4. In an extension table, the combination with a pair of table tops mounted upon extension slides, of a leaf housed beneath the table tops and movable vertically, said leaf presenting cammed surfaces sloping in the longitudinal direction thereof, and a swingable means arranged longitudinally of the table and movable into and out of direct operative engagement with said cammed surfaces in its swinging movement to raise and lower said movable leaf.
